UNITED STATES PATENT OFFICE.

MORRIS ROSENWASSER, OF NEW YORK, N. Y.

LEGGING.

No. 888,745.

Specification of Letters Patent.

Patented May 26, 1908.

Application filed March 29, 1906. Serial No. 308,628.

To all whom it may concern:

Be it known that I, MORRIS ROSENWASSER, residing at New York, in the county of New York and State of New York, have invented certain new and useful Improvements in Leggings, of which the following is a full, clear, and exact description, such as will enable others skilled in the art to which it appertains to make and use the same.

10 My invention relates to garments, and in a more specific relation to leggings. One of its objects is to provide a more efficient way of fastening the leggings upon the leg of the wearer than has hitherto been devised.

15 Another object is to provide a legging characterized by increased wearing qualities, combined with a more slightly appearance than is found in the types now in use.

20 A further object is to provide in a legging designed to be worn over the shoe more effective means for securing the same upon the leg, whereby the objectionable straps or stirrups which pass beneath the foot are entirely eliminated.

25 Other objects will be in part obvious and in part pointed out hereinafter.

The invention accordingly consists in the features of construction, combinations of elements and arrangement of parts shown in the 30 accompanying drawing, and the scope of the application of which will be indicated in the following claims.

In the accompanying drawing, wherein I have illustrated one of the various possible 35 embodiments of my invention, Figure 1 is a view in elevation thereof, showing the legging positioned upon the leg, some of the parts being broken away to show certain features of construction. Fig. 2 is a view in 40 perspective, showing the same.

Similar reference characters refer to similar parts throughout both views of the drawing.

One of the most serious disadvantages 45 arising from the use of leggings as now constructed resides in the employment of straps or stirrups which extend from the lower edges of the legging and are passed underneath the foot on the outside of the shoe. 50 This stirrup is thus brought into contact with dirt and moisture, and on account of such severe usage soon rots away or wears out, rendering the whole legging unfit for further wear although the other parts thereof may

be capable of performing efficient service for 55 a much longer period. By my invention, which I shall presently describe in detail, I have provided a structure wherein these objectionable stirrups or straps are entirely done away with, and yet the legging is not 60 only more securely fixed upon the leg of the wearer but is more readily positioned thereon and removed therefrom, and is moreover capable of a wide range of adjustment upon the leg.

I obtain the above among other advantages through the provision of a structure of the nature of that hereinafter described.

Referring now to the drawings, the legging 1 is comprised by a plurality of suitably shaped 70 strips of cloth, leather or other suitable material, sewed together to provide a contour corresponding approximately to the shape of the leg. In the present instance I employ four strips and provide a seam in the rear 75 portion of the legging at 2 and a seam at each of the side portions, one of which is shown, at 3, the open edges coming at the front portion of the leg. I have found this manner of constructing the legging possessed of many 80 advantages, among which are the ability to secure a better fit and a more efficient operation of the devices employed to secure the same upon the leg.

One of the meeting edges 4 is provided 85 with a series of fastening devices as at 5, and the other edge 6 is provided with a series of eyelets 7 similarly arranged, through which the lace 8 passes, the portions of said lace intermediate said eyelets looping over the fastening devices arranged opposite thereto. In this embodiment lace 8 is secured at one end in an eyelet 9 in edge 4 of the legging, the opposite end of said lace being adapted to be passed through a similar eyelet 10 in 95 the upper end thereof. It will be understood, of course, that any suitable fastening means, such as buttons or clasps, may be employed if desired. The legging when in position upon the leg extends over the upper 100 or ankle portion of shoe 11 and also covers a portion of the body of the shoe, as shown in Fig. 1. Secured to shoe 11 at its upper rear portion is a tag, shown herein as being constituted by the usual loop, and is designated 105 by 12. Secured to the rear wall of the legging interiorly thereof, as by rivets 13 or other suitable means, is a member 14 pro-

vided with a pair of loops 14', one of said loops being disposed above the other. Loops 14' are arranged to come adjacent loop 12 upon the shoe when the legging is positioned upon the leg, as clearly shown in Fig. 5. Loops 12 and 14' are adapted to be connected together by a string or tape 15, which when tied fastens the legging securely to shoe 11, and prevents the same from upward 10 or downward movement upon the leg.

The method of using my invention, although the same should to a large extent be obvious from the foregoing description, may now be explained. In adjusting the 15 legging upon the leg, loop 12 and one of loops 14' nearest the top of the shoe are first tied together by cord or tape 15, when the legging is passed around the leg and secured thereabout by means of lace 8.

20 It will accordingly be seen that I have provided a construction which is especially well adapted to attain the objects of my invention. The legging being entirely free from the usual straps or stirrups is rendered more 25 serviceable and is moreover more effectively secured upon the leg. By reason of the provision of the plurality of loops upon the legging the same may be readily attached to shoes having uppers of various heights, and 30 a relatively wide range of adjustment is also afforded on account of the adjustable character of the tying means. Other advantages reside in the ease with which the legging can be positioned upon and removed 35 from the leg, and its sightlessness of appearance.

As many changes could be made in the above construction and many apparently widely different embodiments of my invention 40 could be made without departing from the scope thereof, I intend that all matter contained in the above description or shown in the accompanying drawing shall be interpreted as illustrative and not in a limiting 45 sense. I desire it also to be understood that the language used in the following claims is intended to cover all of the generic and specific features of the invention herein described and all statements of the scope of 50 the invention which, as a matter of language, might be said to fall therebetween.

Having described my invention, what I

claim as new and desire to secure by Letters Patent is:—

1. A legging of the class described, the leg portion of which is adapted to be wrapped about the leg and secured thereabout by means connecting its meeting edges, said legging having a flexible member secured to the inner surface thereof, which is adapted to be 55 detachably connected with a shoe or similar article of foot covering to prevent the legging from rising upon the leg of the wearer.

2. A legging comprising a portion adapted to be positioned about the leg and ankle and 60 having a loop secured to its inner surface, said loop being adapted to be tied or otherwise secured to a similar loop of a shoe or other foot covering.

3. A legging comprising leg and ankle portions adapted to be positioned about said parts, said ankle portion having a loop secured upon its inner wall adjacent a similar loop extending from a shoe or other foot covering, and a flexible cord or tape for fasten- 70 75 ing together said loops.

4. In combination, a shoe or other foot covering provided with a loop extending therefrom, a legging adapted to be positioned about the leg and also about a portion of said 80 shoe, said legging being provided with a plurality of loops upon its inner surface, and a cord or tape adapted to be passed through one of said loops and through the loop upon said shoe, the ends of said cord or tape being 85 adapted to be tied together whereby said legging is to be connected with said shoe.

5. A legging of the class described comprising a strip of flexible material adapted to be wrapped about the leg and fastened thereabout at its free meeting edges, a plurality of loops secured interiorly of the rear portion of the legging intermediate the ends thereof, and a cord extending through one of said 90 loops and adapted to be passed through a 95 loop of a shoe, said cord being adapted to fasten said loops together and hold the legging against upward movement.

In testimony whereof I affix my signature, in the presence of two witnesses.

MORRIS ROSENWASSER.
